CLAIM

The ornamental design for a neck pillow with light, as shown and described.

DESCRIPTION

FIG. 1 is a front, top and right side perspective view of a first embodiment of a neck pillow with light showing my new design;

FIG. 2 is a top plan view thereof shown in an alternate position wherein the neck pillow with light is in a less open state;

FIG. 3 is a bottom plan view thereof;

FIG. 4 is a rear elevational view thereof;

FIG. 5 is a front elevational view thereof;

FIG. 6 is a right side elevational view thereof;

FIG. 7 is a left side elevational view thereof;

FIG. 8 is a front, top and left side perspective view of the neck pillow with light of FIG. 1 being worn by a user;

FIG. 9 is a front, top and right side perspective view of a second embodiment of a neck pillow with light showing my new design;

FIG. 10 is a top plan view thereof shown in an alternate position wherein the neck pillow with light is in a less open state;

FIG. 11 is a bottom plan view thereof;

FIG. 12 is a rear elevational view thereof;

FIG. 13 is a front elevational view thereof;

FIG. 14 is a right side elevational view thereof; and,

FIG. 15 is a left side elevational view thereof.

In the drawings, the broken lines represent environmental structure forming no part of the claimed design.
